UNITED STATES PATENT OFFICE.

BERNICE J. NOYES, OF BOSTON, MASSACHUSETTS.

MULTIPLE-SIGNAL TRANSMITTER.

SPECIFICATION forming part of Letters Patent No. 451,512, dated May 5, 1891.

Application filed September 22, 1890. Serial No. 365,707. (No model.)

To all whom it may concern:

Be it known that I, BERNICE J. NOYES, of Boston, county of Suffolk, State of Massachusetts, have invented an Improvement in Multiple-Signal Transmitters, of which the following description, in connection with the accompanying drawings, is a specification, like letters and figures on the drawings representing like parts.

10 Multiple-signal transmitters have heretofore been made which comprised a train, an operating-lever therefor, and a removable signal-wheel, and such a signal-transmitter is operated by placing the signal-wheel on its 15 operating-shaft in correct position and thereafter moving the operating lever or pull to wind up or to start the train. Considerable time is required to accomplish these several movements, and it is the object of this invention to so construct a multiple-signal transmitter of this class that it will be self-starting, to thereby save a portion of the time which is now consumed in operating it.

While many ways may be devised for carrying out my invention in detail, I have herein shown the train as normally wound up and have provided a suitable let-off, and have so constructed other parts that as the signal-wheel is placed in position on its shaft the 30 said let-off will be moved and the train released.

Figure 1 shows in front elevation a multiple-signal transmitter embodying this invention; Fig. 2, a detail of one of the signal-wheels to be referred to; Fig. 3, a horizontal section of the removable signal-wheel, showing how it fits on the shaft; and Fig. 4, a similar view to Fig. 2, showing the signal-wheel on the end of the shaft, but not pushed forward to move the let-off.

The train herein shown and to which my invention is applied comprises a toothed wheel a , arranged on a winding-shaft a' and in mesh with a pinion a^2 , (see dotted lines,) 45 secured to a shaft a^3 , to which shaft is secured a toothed wheel a^4 , engaging a pinion a^5 , (see dotted lines,) secured to a shaft a^6 , to which a toothed wheel a^7 is secured, which engages a pinion a^8 , secured to a shaft a^9 , carrying the escape-wheel a^{10} , adapted to co-op-

erate with any suitable pallet. A signaling-key is provided, consisting of a stationary contact-pen 2 and a movable contact-pen 3, the latter occupying a suitable position to cooperate with a signal-wheel b , which is herein 55 shown as secured to a shank b' , to which a knob b^2 is secured and by which it may be removed at will. This signal-wheel b has formed on or secured to it a tapering hub b^3 . (See Fig. 2.)

The signal-wheel is removable at will from its shaft a^6 , in order that another wheel, having a different predetermined signal thereon, may be substituted. A let-off is provided for the train, consisting, as herein shown, of a bell-crank lever pivoted at c to the framework, one arm, as c' , of which has on it a pin c^2 , which engages a pin c^3 on the wheel a^4 , and the other arm, as c^4 , of which normally bears against a pin c^5 on the frame. The arm c^4 is 60 of suitable length to lie in the path of movement of the tapering hub b^3 when in its normal position against the pin c^5 , so as to be moved by said hub when the signal-wheel is placed on the shaft a^6 . As the let-off $c' c^4$ is 65 moved by the tapering hub b^3 , this pin c^2 releases the pin c^3 and thereby the train. The signal-wheel b will be revolved by means of the shaft a^6 until the pin c^6 on the wheel a^4 , arranged in a different distance from the axis 70 of rotation of said wheel, engages and strikes the pin c^2 on the arm c' , which at this time will be in the dotted-line position shown. The train will thus be stopped, and the signal-wheel being removed the let-off will resume 75 its normal full-line position shown, and the train will again start and run until the pin c^3 engages the pin c^2 , when the train is again stopped. Thus it will be seen that simply by the act of placing the signal-wheel on its shaft 80 in position to operate the train is started and the signal will be transmitted, thereby saving the time of the attendant in operating the lever. Although this time saved is small, yet in a device of this kind—when employed, for 85 instance, as a wagon-call transmitter for police-signal systems—one or more seconds is of vital importance.

I do not desire to limit my invention to the specific construction shown for carrying out 90

the desired results in detail, as it is obvious that it may be changed and yet come within the scope of my invention.

I claim—

- 5 1. In a multiple-signal transmitter, a train and a let-off, combined with a removable signal-wheel and means controlled by the signal-wheel for moving the let-off, substantially as described.
- 10 2. In a multiple-signal transmitter, a train and a let-off, combined with a signal-wheel and a hub moved by it for effecting movement of the let-off, substantially as described.
- 15 3. In a multiple-signal transmitter, a train and a circuit-changing device, a co-operating part of which is removable, combined with a let-off for said train, movement of which is effected by said co-operating part of the circuit-changing device, substantially as de-
- 20 scribed.
- 25 4. In a multiple-signal transmitter, a nor-

mally-wound-up train, one of the wheels of which has on it two pins $c^3 c^6$, and a circuit-changing device, a co-operating part of which is removable, combined with a let-off adapted to engage the pins $c^3 c^6$, as described, and means controlled by said removable co-operating part of the circuit-changing device for effecting movement of said let-off, substantially as described.

5. In a multiple-signal transmitter, a normally-wound-up train and a let-off therefor, combined with a removable signal-wheel and a tapering hub for moving said let-off, substantially as described.

In testimony whereof I have signed my name to this specification in the presence of two subscribing witnesses.

BERNICE J. NOYES.
